UNITED STATES PATENT OFFICE.

HARRIS H. HAYDEN, OF NEW YORK, N. Y., ASSIGNOR TO THE AUTOMATIC PARCEL DELIVERY COMPANY, OF SAME PLACE.

STORE-SERVICE APPARATUS.

SPECIFICATION forming part of Letters Patent No. 272,686, dated February 20, 1883.

Application filed October 13, 1882. (No model.)

To all whom it may concern:

Be it known that I, HARRIS H. HAYDEN, of the city, county, and State of New York, have invented certain Improvements in Store-Serv-
ice Apparatus, of which the following is a speci-
fication.

My invention relates to that class of store-
service apparatus in which the goods and cash
are conveyed between a main desk and the
10 counters or stations by means of carriers hav-
ing pendent baskets or receptacles; and my
invention consists of certain improvements,
hereinafter described, in the construction and
support of the ways and carriers, and in the
15 means for placing the carriers upon and re-
moving them from the ways.

In the drawings, Figure 1 is a side view,
slightly in perspective, of part of the way of a
20 store-service apparatus, illustrating my invention.
Fig. 2 is a transverse sectional elevation
of the same, enlarged. Fig. 3 is a perspective
view of the double ways, supports, and stays,
seen from the level of the ceiling. Fig. 4 is a
25 plan view of part of one of the ways and car-
rier in section. Fig. 5 is a side elevation of
part of the same with locking device. Fig. 6
is a side view of one of the carriers. Figs. 7
and 8 are views illustrating the adjustable
30 connection for the rails. Figs. 9 and 10 are views
illustrating the method of fastening the stays
to the rail.

The track or way is constructed to afford two
bearings, $x x$, upon opposite sides of a continu-
ous slot or channel, y , (see Fig. 4,) the wheel
35 or wheels a of the car W resting upon both of
the ways, and the basket f being connected to
the frame of the car by means of a stem, d ,
preferably round in cross-section, so as to af-
ford as little bearing as possible in case of ac-
40 cidental contact between the stem and the way.

As shown, the carrier is provided with two
wheels, $a a$, of such width as to fit nicely, with-
out friction, upon the edges of the rails or strips
45 g , and with a central annular rib, which re-
mains between the rails as the wheel revolves,
and prevents lateral play sufficient to bring
the rod d against the edges of the strips. By
this means I almost entirely prevent any fri-
50 tion tending to retard the movement of the
carrier upon the way. This construction pre-
vents absolutely the possibility of derailment,

and reduces to a minimum the lateral oscilla-
tion of the carrier. To prevent possible con-
tact between the stem d and the inner edges
of the strips g , should any oscillation of the 55
carrier occur, I set the rails at an angle, as
shown in Fig. 2, or bevel the inner edges of
the rails.

The ways may be constructed of various
forms to secure the bearings and slot afore-
said. As shown in the drawings, each way
A consists of two hollow rails, $q q$, similar in
construction to those described in my Patent
No. 260,568, secured to yokes C, and separated
to form the slot y , the yokes being suspended
65 from a rod, B, supported by chains or cords D
from the ceiling F.

Heretofore ways have been supported either
by hangers fastened rigidly to the ceiling or
on brackets attached to the shelving or on a
70 frame-work resting on the floor. The improve-
ment here shown consists in suspending the
"ways," by means of chains or other light and
strong material, from the ceiling F, the sus-
pension chains or cords D being passed
75 through eyes O and fastened therein, when
properly adjusted, by set-screws v. By having
the cords or chains of uniform length the tracks,
when hung, will be exactly level and equal,
and will balance each other. By pulling down
80 the end of one track the companion track will be
raised to a height exactly corresponding thereto,
and thus a regular and uniform grade or incline
of both tracks sufficient to give the carrier the
proper impetus is easily and quickly secured. 85
Any other flexible suspension may be used
with or without the counterbalancing feature,
as the mere use of a flexible suspension will
reduce noise and facilitate erection. When
the position is determined, the further shifting
90 of the chains is prevented by the setting of
set-screws v v, or by cross-pins inserted where
the chains enter the eyes O O, or otherwise.
Longitudinal swaying and lateral displacement
of the ways are prevented by means of braces z
95 z, connected, Fig. 3, adjustably to upright rods
z', to accommodate the varying relative position
of the two ways as graded. As shown in Fig.
3, the track A' is graded so that a carrier will
pass in the direction of the arrow, and the 100
track A is inclined in the reverse direction.

Bracing wires or cords J J, Fig. 2, can be

put across from the rod B of one way to the rail of the opposite way. The track is further secured against swaying by guys or stays R² R², which pass up at the proper angle to the ceiling, or by similar stays, (or fixed rods,) which are fastened to the counters or shelving below, or elsewhere.

It is important that the rails q q should be perfectly straight on their upper surfaces. For this reason, to overcome any inequalities in the rails, and also for increased convenience in setting up the apparatus, I use rails formed of metal, bent to form inturning back flanges, and attach the rails to the yokes C by means of 15 separate eye-pieces u' u', which slide into the rails, said pieces having pins s', which are dropped into holes in the lower ends of the yokes C, where they can be adjusted to set the rails and fastened in place by set-screws. One 20 of the rails q is severed to form slots r at the points where it is convenient to place the carriers upon the way, such slots permitting the passage of the stem d from the outside of the rail to the slot y when the carrier-wheels are 25 above the way; but after the wheels take their bearing upon the rails q q, the central flange prevents any such lateral motion as will permit the stem to pass into the slot and the car to fall off the track. Double guides t t, Fig. 4, 30 secured to plates inserted in the hollow of the rail adjacent to the slot r, facilitate the introduction of the stem into the slot in placing the carriers upon the way. These guides may slide in the slotted rail, and may be thrown together by means of springs u u, as shown, and the slot will thus be closed as soon as the car 35 stem has passed in.

The carriers may be stopped in any suitable manner and removed by hand at points where 40 the rails are slotted, as shown in Fig. 3, where a stop, W', is shown on the return-track. I prefer, however, to deflect the carriers to a stationary rail-section, as shown in Fig. 1. For this purpose a section, P, of the way is made 45 movable and hinged at R R to the main stationary portion, so that the opposite end may be swung downward to the end of the stationary section A², suitably supported upon the main way by ring-braces p p, through which 50 cars can pass and onto which the proper carrier will run, the movable section being then returned to place for the passage of other carriers. To prevent a following carrier from running onto the section P when the latter is depressed, I use a guard or gate, H, which drops 55 automatically at the rear of the pivot-point when the section P is depressed. The movements of the section P may be effected by hand. I prefer, however, to provide means whereby 60 each carrier may be automatically removed on reaching the proper station. For this purpose section P should be counterbalanced by a spring or weight, so as to occupy a horizontal position until depressed by the weight of the 65 carrier, and should be secured in such horizontal position by a locking device operated

only by the carriers which are to be detached at such point. As shown in the drawings, the section P is counterbalanced by a weight, l, connected to a cord, k, passing over a pulley, and 70 attached to a yoke, C', connecting the rails of said section. A catch, M, is pivoted to the rod B, and has a lip or shoulder, i, which extends beneath the yoke C' and holds the section P in place until the catch is struck at its 75 lower point by the cross-pin b of the carrier which is to be detached. The contact of this cross-pin swings out the catch and releases the section P, when the weight of the carrier will cause such section to drop until the carrier 80 passes onto the section A², when the weight l will restore the section P to its horizontal position, and the catch, operated by its weight or by a spring, y', will swing under the yoke C' and secure it. 85

The gate H is connected by a cord, k', to the cord k, so that the said gate will be raised as the section P assumes a horizontal position, and lowered when said section is depressed. It will be obvious that said gate may be made 90 in different forms and differently operated to accord with the movements of the section P, and that locking devices constructed and operated differently from that described may be used with like results. 95

The cross-pins b upon the carrier may be made adjustable by connecting them to plates g, pivoted to the carriers and slotted for the passage of binding-screws e, by which the plates may be clamped in position after their 100 proper adjustment.

Although I have described the rails as being of metal, they may be made of light strips of wood, and, whether of wood or metal, may have side flanges to aid in guiding carriers of any 105 suitable construction.

To facilitate the placing of the carriers in position from below and avoid the necessity of using elevating devices, each carrier may be provided with a permanent downwardly-projecting stem or handle, g', by means of which it may be elevated to a way at a considerable height above the head. 110

A convenient form of basket for the carrier is a half-cylinder, f, open at the top and lying 115 within a ring, e, secured to the stem d, and provided with a handle, g', and supporting the basket without interfering with the placing of articles of large size in the basket.

It will be obvious that the movable section 120 P may be used as a means of putting the carriers upon the track. Thus the section may be pulled down, a carrier placed upon the end of the same and held by a suitable stop, and the section then raised into line with the way, onto which the carrier will pass. In such cases the counter-weight may be sufficient to elevate the way and carrier with the goods it contains; or the section may be raised by means of a handle or other appliance. 125

In a separate application for Letters Patent I have shown a movable send-off section ar- 130

ranged at an angle to the main line, and I do not claim here, broadly, the employment of such movable sections, the distinguishing feature of this invention being the use of movable portions of the main track in line therewith, as described.

I claim—

1. The combination, in a store-service apparatus, of a way consisting of parallel rails forming a continuous central slot, *y*, and carriers with wheels adapted to said parallel rails, and with baskets or holders suspended therefrom by stems extending through said slot, substantially as set forth.
2. The way consisting of separated strips or rails *q q*, connected by overarching yokes *C*, substantially as set forth.
3. The combination, in a way, of rails *q q*, connected by overarching yokes and spread apart from the upper to the lower edges, as specified.
4. The combination, with the way and yokes *C*, of a bar, *B*, supporting said yokes, as set forth.
5. The way consisting of parallel separated bars, with slots *r* extending through one of said bars, for the purpose set forth.
6. The combination, with the way having slots *r*, of guides *t*, as specified.
7. The way consisting of two parallel sections, with slots in one of said sections and with automatic closing devices, substantially as set forth.
8. The way provided with a movable section, *P*, in combination with a locking device constructed to be operated by the carriers, and with a counter-balance and an auxiliary section, *A²*, substantially as set forth.
9. The combination, with the way and its movable section, of a gate and appliances for closing and opening the same as said section is operated, substantially as specified. 40
10. The combination, with the way and its movable section, of a locking device provided with stops or projections, and carriers provided with adjustable stop-pins *b* to act upon said locks, substantially as set forth. 45
11. The carrier with wheels adapted to ways consisting of parallel rails, with an intervening continuous slot, and provided with a central dependent stem supporting a receptacle, in combination with said ways, as specified. 50
12. The combination, in a carrier, of a basket, *f*, and a band, *e*, connected to the carrier-frame, and provided with a handle, *g'*, substantially as set forth. 55
13. The combination of the tracks and flexible suspensories and the guys or stays connected to the ways, substantially as specified.
14. The combination of the ways *A A'*, and flexible suspensories connected to both ways and adjustably supported, substantially as specified. 60
15. The eye-pieces *u' u'*, adapted to the rails, and with pins adjustable in sockets in the yokes *C*, as and for the purpose set forth. 65
16. The adjustable braces *z z'*, extending between the tracks, for the purpose specified.

In testimony whereof I have signed my name to this specification in the presence of two subscribing witnesses.

HARRIS H. HAYDEN.
